ABSTRACT OF THE DISCLOSURE

An electro-pneumatic switch includes a housing mounting, a fixed electrical contact and a movable switch arm. A fluid conduit is attached to the housing in a fixed position and has an outlet opening positioned adjacent the switch arm. The outlet opening of the fluid conduit defines a valve seat and a valve member is positioned between the switch arm and the valve seat. An actuating member on the housing moves the switch arm from a position in engagement with the fixed electrical contact to a position out of engagement with the fixed contact. In the out-of-engagement position, the valve member is biased against the valve seat by the switch arm to close the outlet opening. The switch arm may be biased to one position by an over-center snap-acting spring arrangement.

BACKGROUND OF THE INVENTION

This application pertains to the art of electro-pneumatic switching devices, and more particularly, to such devices which are selectively operable to open or close an electrical circuit while simultaneously opening and closing the outlet of a fluid conduit. The invention is particularly applicable to controlling bi-stable fluid amplifiers and will be described with particular reference thereto, although it will be appreciated that the invention has broader applications and could be used in any electro-pneumatic control system.

An electro-pneumatic switching device includes features of both an electrical switch and a pneumatic valve. It is desirable to combine features of both devices so that part of the movable members in the electrical switch also serve as components of the pneumatic valve. It is also desirable to rapidly open and close the pneumatic valve to provide positive operation of other devices in the pneumatic system. In addition, it is desirable to accurately predict the sequential operation of both the electrical switch and the pneumatic valve. Prior devices which combined pneumatic valves with electrical switches have been so arranged that it is difficult to predict whether the electrical circuit will be made or broken before the pneumatic circuit is opened or closed. In addition, prior devices have been rather slow acting as far as opening and closing the pneumatic valve is concerned. Other prior art arrangements have required movement of a pneumatic tube in order to open and close the valve. It would be desirable to have movement of the electrical switch arm itself actuate the pneumatic valve. In a more limited aspect, it would be desirable to have no movement of the pneumatic tube when it connects to an electrical switch housing and to arrange the valving inside of the switch housing so that space is conserved and exterior movable parts are minimized.

SUMMARY OF THE INVENTION

The present invention contemplates a new and improved electro-pneumatic switching device which overcomes previous problems and provides a new arrangement which is far simpler, both in operation and manufacture, and also very compact, by having no movable pneumatic valve parts exterior of the switch housing. In

2

accordance with the present invention, there is provided an electro-pneumatic switching device in which a snap-acting electrical switch arm operates to open and close a pneumatic valve, as well as making and breaking an electrical circuit. More specifically, the present invention includes a conventional switch housing enclosing a snap-acting switch arm which cooperates with a fixed electrical contact. A fluid conduit having an outlet opening is positioned in the housing adjacent the switch arm and the switch arm cooperates with the conduit to open and close the outlet opening. In a more limited aspect, a fluid conduit is secured to the housing in a stationary position and the fluid conduit has an outlet opening inside of the housing positioned adjacent the switch arm. The switch arm cooperates with valve means to selectively open and close the outlet opening as the switch arm moves between two positions. In accordance with a still further limited aspect of the invention, an electro-pneumatic switching device is mounted to a timer assembly which is releasably mounted in an enclosure. The enclosure and the timer assembly include an automatic fluid coupling so that the pneumatic conduit to the electro-pneumatic switch is automatically made and broken as the timer assembly is received in, or removed from, the timer enclosure.

It is a principal object of the present invention to provide an electro-pneumatic switching device which is very simple to operate and manufacture.

It is a further object of this invention to provide such a device which utilizes movement of a snap-acting electrical switch arm to open and close a pneumatic valve.

It is another object of the present invention to provide such a device in a manner that leaves no movable valve parts exterior of the switch housing.

35 It is an additional object of the present invention to provide such a device wherein a fluid conduit is secured to the switch housing in a stationary position so that there is no movement of the conduit itself when the valve is operated.

40 It is also an object of the present invention to provide such a device in which rapid sequential operation of the electrical contacts and the pneumatic valve is accurately predictable.

BRIEF DESCRIPTION OF THE DRAWING

The invention may take physical form in certain parts and arrangements of parts, a preferred embodiment of which will be described in detail in this specification and illustrated in the accompanying drawing which form a part hereof.

55 FIG. 1 is a schematic diagram showing the electro-pneumatic switching device of the present invention connected in a fluidic circuit and with the device itself shown in a side elevational view without a cover;

FIG. 2 is a side elevational view of a timer assembly and timer enclosure with which the present invention is usable and with portions cut away for clarity;

FIG. 3 is a rear elevational view of a timer assembly taken in the direction of arrows 3—3 of FIG. 2;

60 FIG. 4 is a rear elevational view of a timer assembly enclosure taken in the direction of arrows 4—4 of FIG. 2;

FIG. 5 is a side elevational view of the timer assembly and timer enclosure of FIG. 2 in assembled position and with portions cut away for clarity;

FIG. 6 is a partial side elevational cross-sectional view of a modified valve arrangement;

FIG. 7 is a partial side elevational cross-sectional view of another modified valve arrangement;

70 FIG. 8 is a partial side elevational cross-sectional view taken in the direction of arrows 8—8 of FIG. 2;

FIG. 9 is a partial elevational cross-sectional view taken in the direction of arrows 9—9 of FIG. 2; and FIG. 10 is a side view of the electro-pneumatic switching device of FIG. 1 in its alternate, valve closed position.

DESCRIPTION OF THE PREFERRED EMBODIMENT

Referring now to the drawings, wherein the showings are for purposes of illustrating the preferred embodiment of the invention only and not for purposes of limiting same, FIG. 1 shows electro-pneumatic switch device A connected in a fluidic circuit with bi-stable fluid amplifier B. The snap-acting switch itself may take many forms and many of them are known to those skilled in the art as "miniature" switches. The switch itself and its specific arrangement for providing snap action may take many forms which are well known in the art. Only one of such mechanisms will be described in some detail as an example of one such snap-acting mechanism.

Electro-pneumatic switching device A includes a housing 12 having an upstanding peripheral wall 14 defining a central recess cavity 16. Wall 14 of housing 12 has a groove 17 and recess 18 formed therein. A flat and elongated electrical lead C has end legs 20 and 22, and an intermediate portion 24. Leg 22 is received in recess 18 and intermediate portion 24 is received in groove 17 to fix lead C against movement relative to housing 12. Leg 20 may have an electrical wire 26 connected thereto as by solder at 28. The flat upper surface 30 of intermediate portion 24 of lead C has an electrical contact 32 secured thereto in a well known manner.

Wall 14 of housing 12 has another groove 34 and recess 36 formed therein to respectively receive intermediate portion 38 and the end portion of leg 40 of electrical lead D which has another leg 42 connected to an electrical wire 44 as by solder at 46. Reception of intermediate portion 38 and leg 40 in groove 34 and recess 36 fixes electrical lead D against movement relative to housing 12. Electrical lead D is formed with a notch 48 in which a pointed end 50 of a pivot member E is received. The other end of pivot member E is formed with a notch 52 receiving a cross piece 54 of switch arm G. Switch arm G includes downwardly extending flanges as at 56 to provide stiffness for the switch arm. Switch arm G includes an integral deformed portion 58 defining a snap-spring having its end received in notch 60 of electrical lead D. Switch arm G has a cross piece 62 at its other end on which a valve member 64 is mounted. In this regard, valve member 64 may simply be a conventional switch contact as found in a double pole single throw switch. Secured beneath cross piece 62 is another electrical contact 66 for cooperating with contact 32 of electrical lead C. It will readily be seen that an electrical current path is established through electrical lead D to switch arm G and electrical contact 66, and also through electrical lead C to electrical contact 32. Wall 14 of housing 12 has another groove 68 formed therein and reciprocally receiving an actuating member H which is formed with an enlarged end portion 70 positioned inside cavity 16 so that the outward reciprocating movement of actuating member H is limited.

Snap spring 58 is deformed as shown in FIG. 1 and normally biases switch arm G to the left in FIG. 1. Switch arm G cannot move to the left in the position shown because cross piece 54 is engaged with notch 52 of pivot member E. Pivot member E cannot move because its pointed end 50 is engaged in notch 48 and its other end engages against the bottom 74 of enlarged portion 70 on actuating member H. Snap spring 58 connects with front cross piece 62 of switch arm G to define a pivot point at 76 and the engagement of rear cross piece 54 with notch 52 defines a rear pivot point. The line connecting these two pivot points is below the point of engagement of snap spring 58 with notch 60 so that switch arm G is also biased downwardly about the rear pivot

point to normally hold contact 66 in engagement with contact 32. Reciprocating movement of actuating member H inwardly deeper into cavity 16 causes pivot member E to pivot upwardly in notch 48 due to engagement of body 74 of enlarged portion 70 with the end of pivot member E. This pivotal movement raises notch 52 and cross piece 54 until a line connecting notch 52 with pivot point 76 is above notch 60. When this occurs, snap spring 58 will be exerting an upward force on cross piece 62 of switch arm G and will cause rapid separation of contacts 32 and 66 in an upward snap acting movement. In this position, notch 48 of pivot member E is still above the line connecting notch 52 and pivot point 76 so that snap spring 58 will be exerting a turning moment on switch arm G tending to move notch 52 and cross piece 54 back to its rest position. Thus, releasing actuating member H causes switch arm G to snap back to its original position due to the turning moment moving notch 52 downwardly until the line connecting pivot point 76 with notch 52 is below notch 60.

Wall member 14 of housing 12 is formed with an arcuate groove 80 which receives a tubular fluid conduit 82. Conduit 82 may be formed with, or have secured thereto, shoulder portions 84 and 86 positioned respectively on the outside and inside of wall 14 to prevent axial movement of conduit 82. It will be recognized that shoulders such as 84 and 86 could be eliminated and conduit 82 simply secured in arcuate groove 80 by any suitable adhesive in a well known manner. Fluid conduit 82 includes an outlet opening 90 opening within cavity 16 and housing 12. The peripheral edge of outlet opening 90 defines a valve seat for cooperation with valve 64 on switch arm G. Air flowing through outlet opening 90 is exhausted to atmosphere from cavity 16 through a groove 92 formed in wall 14 of housing 12. It should be recognized that while opening 90 is called an outlet opening it can be either an opening for exhausting air or for admitting air. That is, conduit 82 can either be a pressure line or a vacuum line.

With the parts arranged as shown in FIG. 1, an electrical circuit is established through lead C, contact 32, contact 66, switch arm G and lead D. Valve member 64 is positioned downwardly away from outlet opening 90 so that air can freely flow through outlet opening 90. Axial movement of actuating member H inwardly deeper into cavity 16 will cause a snap acting movement of switch arm G as previously described. This rapidly separates contacts 32 and 66 to open the electrical circuit. At the same time, valve member 64 snaps upwardly and is shaped to fit in sealing engagement with the periphery of outlet opening 90. This movement shuts off the flow of air through conduit 82. Releasing actuating member H will cause a downward snap acting movement of switch arm G to once again bring contacts 32 and 66 into engagement and to separate valve member 64 from outlet opening 90. It will be understood by those skilled in the art that such members as housing 12, actuating member H and conduit 82 may be made of synthetic plastic material if so desired. However, other materials may be used as well and materials form no part of the present invention. A suitable cover member may be secured to the top periphery of wall 14 of housing 12 by suitable bolts or rivets passing through holes in the cover aligned with suitable holes 110 and 112 in housing 12.

The pneumatic control arrangement previously described may be used to control a bi-stable fluid amplifier B. A suitable coupling 118 defines an inlet to a flow channel 120 of amplifier B. Coupling 118 may be connected with a suitable supply of compressed air through a tube 122. Flow channel 120 is divided into two separate outlets 124 and 126 at the other end of amplifier B. Suitable couplings 130 and 132 are connected with outlets 124 and 126, and tubes 134 and 136. Flow channel 120 is intersected by a pair of laterally extending flow channels 140 and 142 which in turn are connected

with suitable couplings 144 and 146. Coupling 146 is connected by a tube 148 to a T 150 having a restricted area 152 and a connection 154 to another suitable source of compressed air 156. T 150 is connected at its other end with a tube 160 which in turn is connected to flow conduit 82 leading to housing 12. Coupling 144 may be connected through a tube 162 to another electro-pneumatic switching device in the same manner as described for coupling 146.

In operation, pressurized air flows from source 156 through line 154 and T 150 to outlet opening 90 in electro-pneumatic switching device A. With the parts arranged as shown in FIG. 1 outlet opening 90 is open and air will be exhausted through groove 92 and wall 14 of housing 12. Restricted portion 152 of T 150 prevents any substantial flow of air to lateral flow channel 142. Pressurized air flowing through flow channel 122 and coupling 118 to flow channel 120 in amplifier B may be made to hug the wall of either outlet opening 124 or 126 due to the Coanda effect as is well known in the art of fluidics. For example, with air flowing through flow channel 120 and hugging the wall of outlet 126 so that no air is flowing through outlet 124, electro-pneumatic switching device A may be actuated to close outlet opening 90 with valve 64 as previously described. This blocks off flow of air through outlet opening 90 and causes air to flow from source 156 past restricted portion 152 and into lateral channel 142. This flow of air through lateral channel 142 will strike the air flowing through channel 120 and cause the main air stream to divert or transfer from outlet 126 over to outlet 124. Connection of lateral flow channel 140 with another electro-pneumatic switching device may be used to transfer the main air stream selectively from flow channel outlet 124 to 126 in the same manner. As is well known, once the main air stream is changed from outlet 126 to 124 as described, it will remain flowing through outlet 124 due to the Coanda effect even though outlet opening 90 is again opened to remove any signal from lateral flow channel 142. Outlets 124 and 126 of fluid amplifier B may be connected to suitable pulse processing fluidic circuits in a well known manner. It will be understood by those skilled in the art that the electro-pneumatic switching device of the present invention could be used in many other vacuum or pressurized pneumatic control systems.

Referring now to FIG. 2, there is shown a timer assembly J and a timer assembly enclosure K. Details of members J and K may be found with reference to U.S. Pat. No. 3,054,023 to Blecker et al., issued Sept. 11, 1962. A suitable timer assembly may be found in the form of a counter in U.S. Pat. No. 2,735,915 to Hagen, issued Feb. 21, 1957, or U.S. Pat. No. 3,355,602 to Erickson, issued Nov. 28, 1967. The timer mechanism per se forms no part of the present invention. As is well known, hollow rivets may be passed through holes 110 and 112 of housing 12 in FIG. 1 to secure the cover onto the housing. When hollow rivets are used screws 180 and 182 in FIG. 2 may be passed therethrough and thread into suitable holes in a mounting bracket M on timer assembly J. A flat plate Y may be secured over switching device A by screws 180 and 182. Plate Y may include a downwardly projecting tang 184 having a pivot pin 186 pivoted thereto. Pivot pin 186 is secured to a lever 188 which extends beneath actuating member H of electro-pneumatic switching device A. Lever 188 includes an upwardly extending leg 190 having a sloped or cammed upper edge 192. A rotatable cam or timing wheel on timer assembly J includes a camming pin 194 which strikes against cam surface 192 on leg 190 at a certain point in the rotational path of cam R. This pivots the forward portion of lever 188 downwardly about pivot pin 186 and raises the rear end into contact with actuating member H to open the electrical circuit and close the outlet opening 90 as previously described with reference to FIG. 1. This arrangement may be used to selectively open and close electric and pneumatic circuits in

any desirable manner. Also, the electric circuit established through electro-pneumatic switching device A may itself control the motor of timer assembly J. In this manner, the timer may be shut off at a predetermined time and the pneumatic circuit will be simultaneously switched to a different condition. The rear end of timer assembly J includes a plurality of electrical connector pins and only one of which is referenced by numeral 202. When timer assembly J is inserted into enclosure K the electrical connector pins as 202 are received in suitable electrical connector sockets as at 204 in the rear of enclosure K. Electrical connections may then be made to the exterior rear of enclosure K as by connecting wires to screws such as 206 which in turn is connected with socket 204. Conduit 82 of electro-pneumatic switching device A may connect to a tube 208 which in turn is connected with a coupling member 210 as shown in FIG. 8. Coupling member 210 may be threaded or barbed to receive nuts or spring type push-ons 212 and 214 to lock coupling member 210 in opening 216 of rear bracket 218 on timer assembly J. The rear wall of enclosure K may then have a coupling secured thereto in a manner similar to FIG. 8. Thus, a coupling member 220 is held to rear wall 222 of enclosure K by nuts or spring type push-ons 224 and 226. Coupling member 220 may be shouldered as 230 and have a suitable elastomeric washer or gasket 232 positioned thereagainst. The inside diameter 234 of coupling member 220 is large enough to receive end 236 of coupling member 210 and when timer assembly J is fully positioned within enclosure K, end 236 of coupling 210 will abut and seal against washer 232 in coupling member 220. Pneumatic line 160 of FIG. 1 may then be connected with coupling 220 of FIG. 2 to establish the pneumatic circuit.

Referring now to FIG. 6, there is shown a modified form of valve device. The same switch mechanism as described with respect to FIG. 1 may be used in FIG. 6. In this arrangement, a tubular fluid conduit 250 has an internal flow path 252 through which air may flow. Conduit 250 includes an outlet opening 254 having a valve member S cooperating therewith. Valve member S includes a solid cylindrical shank portion 256 and a circular flat head portion 258. Shank portion 256 is of sufficiently smaller diameter than flow path 252 so that valve member S may freely slide of its own weight with respect to conduit 250. The diameter of enlarged head portion 258 of valve member S is larger than the diameter of flow path 252 and conduit 250 so that when switch arm G is shifted to its upper position in a manner described with respect to FIG. 1, upper member 64 on switch arm G will strike head 258 of valve S to seal outlet opening 254. When actuating member H is released so that switch arm G returns to its position establishing an electrical circuit valve member S falls away from opening 254 of its own weight and also due to pressure in conduit 250. It will be noted that this type of valve arrangement is not suitable for use when a vacuum pneumatic system is used unless an additional spring is provided to bias valve S to an open position.

FIG. 7 shows another modified valve arrangement in which conduit 82 is formed with a valve seat 260 to cooperate with a ball 262. In both this arrangement, and the arrangement of FIG. 6, the valve member is freely positioned between members 64 on switch arm G and the outlet opening of fluid conduit 82. When switch arm G is in its lower position with contacts 32 and 66 in engagement with one another ball 262 is free of seat 260 so that flow is established through the outlet opening but ball 262 is still slightly within the valve seat so that it cannot be displaced. In the arrangement of FIG. 7, actuation of actuating member H as described with respect to FIG. 1, moves switch arm G upward and engagement between members 64 and ball 262 forces ball 262 upward into sealing engagement with valve seat 260 to close the outlet opening. Releasing actuating member H moves switch arm G back to its lower position and ball 262 drops downward slightly

to open the outlet opening. In this arrangement, as in FIG. 6, the ball valve may not be a suitable arrangement for use with a vacuum system unless an additional spring is provided to bias ball 262 away from its seat. An operative arrangement could be provided without a spring if the vacuum were extremely low and ball 262 were heavy enough to fall away of its own accord.

It will be obvious to those skilled in the art that many other valving arrangements could be provided. For example, a flapper valve or pinch valve could also be provided with the outlet opening of conduit 82 being defined by a highly flexible elastomeric material. In this manner, member 64 on switch arm G or any other suitable member could be used to squeeze the tube or close the flapper valve. In addition, it is obvious that switch arm G could be normally biased to a valve closed position so that operation of actuating member H would open the valve while closing the electrical circuit instead of vice versa as described herein. It will also be readily apparent that member 64 could be positioned forwardly, rearwardly or to the side of bottom contact 66 in order to close a valve at the same time that an electrical circuit is established between contacts 32 and 66. Also, switch arm G could be extended and have an additional switch contact on its upper surface so that an additional electrical circuit would be established at the same time that valve member 64 closed outlet opening 90. In connection with enclosure K, it will be obvious that a suitable hole, such as 300 in FIG. 4, may be provided to exhaust air from the electro-pneumatic switch. While the invention has been described with reference only to certain preferred embodiments, it is obvious that other modifications and alterations than those described will occur to others skilled in the art upon a reading and understanding of this specification.

Having thus described my invention, I claim:

1. In a combined valve and electrical switching device including support means having mounted thereon fixed electrical contact means and movable switch arm means, said switch arm means being movable between a first position in contact with said fixed electrical contact means and a second position out of contact with said fixed electrical contact means, and actuating means for moving said switch arm means from one of said positions to the other of said positions, the improvement comprising: fluid conduit means having an outlet opening in alignment with said fixed electrical contact means and spaced apart therefrom by an air gap and valve means movable between open and closed positions to selectively open and close said outlet opening, said switch arm means extending into said air gap intermediate said outlet opening and said fixed electrical contact means and

cooperating with said valve means for positioning said valve means in one of said open and closed positions in one of said first and second positions of said switch arm means and for positioning said valve means in the other of said open and closed positions in the other position of said switch arm means.

2. The device of claim 1 and further including a timer mounted in an enclosure, said device being mounted in said enclosure, and operating means on said timer for moving said actuating means from said first to said second position at a predetermined point in the operating cycle of said timer.

3. The device of claim 2 wherein said timer is detachably mounted in said enclosure and said device is mounted on said timer to be removable therewith from said enclosure.

4. The device of claim 3 wherein said enclosure has a hole therein for said fluid conduit means and further including automatic coupling means for connecting and disconnecting said conduit means with said hole when said timer is inserted in and removed from said enclosure.

5. A combined valve and electrical switching device comprising: a housing, a fixed electrical contact secured in said housing, a fluid conduit secured in said housing, said conduit having an outlet opening in alignment with said fixed electrical contact and spaced-apart therefrom by an air gap, a movable switch arm carried by said housing having an end portion which extends into said air gap intermediate said electrical contact and said outlet opening, actuating means for moving said switch arm from a first position in engagement with said electrical contact to a second position out of engagement with said electrical contact, said switch arm cooperating with said fluid conduit to selectively open and close said outlet opening when said switch arm is moved between said first and second position.
